ADJUSTABLE FENCE FOR MACHINE TOOLS

Asaka J. Okamuro, Kalamazoo, Mich., assignor to
Atlas Press Company, Kalamazoo, Mich., a corporation of Michigan

Application August 16, 1950, Serial No. 179,695

2 Claims. (Cl. 144—253)

1

This invention relates to fences or guides for machine tools such as jointers which have a table over which the work piece moves and whose path is determined by the fence or guide, and particularly to such a fence which can be adjusted along the table top and also can be adjusted angularly with reference to the table top to assist in beveling or squaring the work piece.

One of the objects of the invention is to provide such a fence which can be manufactured easily and inexpensively.

Another object of the invention is to provide such a fence which may be easily and accurately adjusted.

Another object of the invention is to provide such a fence in which the lower edge of the fence is kept down into contact with the table at all times so that inaccuracy will not creep into the work due to shifting of the fence under pressure of the work piece.

Other objects and advantages of the invention will be apparent to those skilled in the art from the following specification and the drawings in which:

Fig. 1 is a side elevational view partly in section showing one form of the invention;

Fig. 2 is a top plan view of the fence shown in Fig. 1 with portions of the fence broken away;

Fig. 3 is a view similar to Fig. 1 showing the fence in a different adjusted position;

Fig. 4 is a front elevational view of the fence with portions of the fence broken away to show the relationship of the parts;

Fig. 5 is a detailed sectional view taken on the line 5—5 of Fig. 4;

Fig. 6 is a detailed sectional view taken on the line 6—6 of Fig. 5 showing a portion of the clamping mechanism which holds the fence in adjusted position;

Fig. 7 is a top plan view partly in section taken on the line 7—7 of Fig. 5;

Fig. 8 is a top plan view of a fence embodying a different form of the invention;

Fig. 9 is an end elevation of the fence shown in Fig. 8;

Fig. 10 is a detailed sectional view taken on the line 10—10 of Fig. 8;

Fig. 11 is a detailed sectional view of the clamping and adjusting mechanism taken on the line 11—11 of Fig. 8; and

Fig. 12 is a detailed sectional view of the mechanism for anchoring the fence shown in Fig. 8 to the table taken on line 12—12 of Fig. 8.

In general the fence consists of a base which

is movable over the table of the machine tool. It has a fence which is offset laterally from the base and is joined to the base with a link connection. A rod is provided which is also pivoted to the fence and is connected by suitable means for slideable and pivotal movement on the base. It is provided with a clamping mechanism and by sliding this rod longitudinally the angle which the face presents to the work piece on the table may be varied. A second rod is also provided which is pivotally connected to the fence or to the link connection. It is provided with means on the base connecting it for sliding and pivotal movement and is provided with clamping means which may be the same clamping means as are provided for the first mentioned rod. By clamping this rod to the base when the fence has been adjusted to the desired angle, the fence is anchored and cannot be raised or moved away from the table when the machine and fence are in use.

In the form of invention shown in Figs. 1—3, the machine tool which is here a jointer, is indicated generally at 1. It has a table top 2 over which the work piece is moved, a slot 3 and a cutter 4, which projects from the slot.

The fence consists of a base 5 which is slidably mounted on the table top for movement from left to right as viewed in Figs. 1—3. The top of the table is provided with a keyway 6 and a corresponding keyway 7 is provided in the bottom of the base 5. A key 8 fits in these keyways and serves to guide the movement of the base. When it is desired to move the fence for any reason the fence is lifted from the table top and the key 8 is likewise removed, leaving a wide, flat space which is sometimes necessary for special operations.

The base is slotted as indicated at 9 to receive a clamping bolt 10, which is provided with a hand nut 11. The table is suitably apertured at 12 to receive the bolt and the base 5 may be securely anchored in the desired position by merely tightening the hand nut 11.

The fence 13 is preferably of cast material and has a ground face 14, against which the work piece rests when the fence is in use. The lower edge of the fence is beveled, as indicated at 15, to permit adjustment to at least 45° from the table top in a direction toward the base. The fence is mounted in an offset relationship to the base with the face 14 facing away from the base by means of a link connection 16, which is pivotally connected on pivots 17 to the ears 18 on the base. The other end of the

link connection 16 is pivoted on pivots 19 to ears 20 which are mounted on a sheet metal plate 21 which is attached to the back of the fence by means of screws 22. This connection permits the base to be moved to various adjusted positions with its lower edge always in contact with the table.

A rod 23 is pivotally connected to the fence with a pivot 24 which connects with an ear 25 on the plate 21. This pivot 24 is parallel to the pivot 19 link connection but spaced therefrom. The rod 23 is slidably and pivotally connected to the base by means of a bearing 27 which slidably receives the rod 23 in an aperture 28 (Figs. 5 and 6) and which is provided with a shank 29 which is pivotally received in an aperture 30 in an ear 31 which extends upwardly from the base 5. The shank 29 is screw-threaded at 32 to engage a clamping nut 33 which is provided with a hand wheel 34. To adjust the fence to various angular positions, the rod 23 is moved longitudinally in the bearing 27 to the desired position, which pivots the bearing on its shank 29. To clamp the rod in adjusted position, there is a shell 35 which surrounds the bearing 27 and is provided with an aperture 36 through which the rod 23 slides. The aperture 36 is spaced from the bottom of the shell which is apertured at 37 to receive the shank 29 a distance greater than the aperture 28 is spaced from the bottom 38 of the bearing 27, so that when the nut 33 is tightened the bearing 27 is pulled to the right as viewed in Fig. 6, anchoring the rod 23.

A second rod 39 is pivotally connected to the fence at 40. In the form of invention shown, the pivot about which the rod 39 is pivoted is the pivot 19 for the end of the link connection 16. The other end of the rod 39 is slidably and pivotally connected to the base. In the form of invention shown in Figs. 1-7 the end of the rod 39 is looped around as is shown at 41 to form a slot 42 which fits over the shank 29 of the bearing 27. This loop lies between the clamping nut 33 and the ear 31, where it is engaged by a washer 43. This connection permits the rod 39 to slide as the fence is moved to various of its adjusted positions and also to pivot about the shank. When the nut 33 is tightened, the rod 39 is also clamped to the base.

Were it not for the rod 39 and the clamping mechanism, when the fence is in the position shown in Fig. 3, the work piece would raise the fence from the table top, thus destroying the accuracy of the work done on the machine tool.

In the form of invention shown in Figs. 8-12, the machine tool is indicated generally at 101 and the table top is indicated at 102. The base 105 is guided on the table by means of keyway 106 in the table top and keyway 107 in the bottom of the base and the key 108 which fits in the keyways. This arrangement permits the entire fence to be removed from the table top and by removal of the key 108 to provide a completely unobstructed surface.

The base 105 is clamped in adjusted position by an eccentric clamp which is pivotally mounted on the table and which may be swung over the base to clamping position or below the table when an unobstructed surface is desired. The eccentric clamp is indicated at 109 and consists of a rod 110 journaled in the table, the eccentric rod 111 and the adjustable clamping members 112. The fence 113 is cast iron and is provided with a ground work-engaging face 114 and is bevelled as indicated at 115 to make it

substantially the same in material respects as the fence 13. A link connection 116 is provided between the fence 113 and the base 105. It is pivoted on pivots 117 which bear in ears 118 on the base 105. The other end of the link connection 116 is pivoted to the fence with the pivots 119 which are disposed in ears 120 on the fence 113.

A rod 123 is pivotally connected by pivot 124 to the fence 113 through ears 125. The rod 123 is pivotally and slidably connected to the base 105 through a bearing 127 which is provided with an aperture 128 to receive the rod 123. This bearing is suitably supported on threaded tubular members 129 which sit in tapered bearings 130 (Fig. 11) and are screw-threaded in the ears 131 which project upwardly from the base 105. The bearing 127 is screw-threaded at 132 to receive the screw-threaded clamping rod 133 which is provided with a hand wheel 134 for clamping the rod 123 for anchoring it. An indexing mechanism is provided which consists of a plunger 135 adapted to engage in aperture 136 in the rod 123. The plunger 135 is fitted in the bore 137 and is provided with a compression spring 138 biased to urge it toward the rod 123.

A second rod 139, which in this form of the invention is a flat rod, is pivoted at 140 to the link member 116 midway of its pivot points. The other end of the rod 139 is slidably and pivotally connected to the base at its other end 141 by means of a slot 142. A clamping nut 143 is provided for clamping the rod 139 against an ear 131. The slot 142 fits over one of the members 129 for sliding connection.

In using this form of the invention, the clamping of the rod 123 and the clamping of the rod 139 are independent operations, it being necessary to tighten both the wheels 134 and 143 to effect tightening. Of course, if the indexing mechanism 135 is employed it is not necessary to tighten the member 133 through the hand wheel 134 since the indexing mechanism will hold the rod and the connected fence in the desired position. When both the rod 123 and the rod 139 are clamped in position the fence is held rigidly in the desired position with its lower edge down to the table and it is not possible to raise the fence away from the table during use.

It will be apparent to those skilled in the art that only two forms of the invention have been illustrated and that forms of the invention other than these preferred forms may be employed. By illustrating these preferred forms there is no intention of limiting the invention to the specific forms shown.

What is claimed is:

1. An adjustable fence for machine tools having tables over which work pieces are moved comprising a base movable over the table, a fence offset laterally from said base and having a work-engaging face facing away from said base and having a bevelled lower edge for engaging the table having its bevel facing said base, a link connection between said base and fence having one end pivoted to said base and the other end pivoted to said fence on a first fence pivot, a rod having one end pivoted to said fence on a second fence pivot parallel to but spaced from and above the first fence pivot of said link connection, a bearing pivoted on said base and slidably receiving said rod whereby said rod may be adjusted longitudinally for different angular adjustment of said fence, a second rod pivoted to said fence on a third fence pivot spaced downwardly from

said second fence pivot and having its other end looped to form a slot extending longitudinally of said second rod, a pin on said base fitted in said slot to slidably guide said rod and serve as a pivot therefor during adjustment of said fence and means for clamping both of said rods in adjusted position to said base, whereby the fence may be held down to the table and in adjusted angular position.

2. An adjustable fence for machine tools having tables over which work pieces are moved comprising a base movable over the table, a fence offset laterally from said base and having a work-engaging face facing away from said base and having a bevelled lower edge for engaging the table and having its bevel facing said base, a link connection between said base and fence having one end pivoted to said base and the other end pivoted to said fence on a first fence pivot, a rod having one end pivoted to said fence on 20 a second fence pivot parallel to but spaced from and above the first fence pivot of said link connection, means slidably and pivotally connecting said rod to said base, whereby said rod may be

adjusted longitudinally for different angular adjustments of said fence, a second rod pivoted to said fence on a third fence pivot spaced downwardly from the second fence pivot, and means connecting the other end of said second rod slidably and pivotally to said base, and means for clamping both of said rods in adjusted position to said base, whereby the fence may be held down to the table and in adjusted angular position.
